CONDIMENT DISPENSER AND STOPPER

Earl W. Clark, Stuart, Fla.

Application January 26, 1949, Serial No. 72,898

9 Claims. (Cl. 222—190)

1

This invention relates to improvements in dispensers and more particularly to condiment dispensers for materials which are inclined to absorb sufficient moisture so as to make the particles tend to adhere together and also to adhere to the outlets or channels leading from the interior of the dispenser and to adhere to valves or stoppers which may be used to seal up or to regulate the flow of material from or through the dispensing outlets.

One of the primary objects of my invention is to provide a condiment dispenser having a valve or stopper for the dispensing outlet or channel that will aid materially in keeping the contents dry and free running and also one that will not stop up or become clogged at the dispensing outlet valve or stopper.

Another object is to provide a valve or stopper for the dispensing outlet that will automatically open when the dispenser is inverted and also a stopper or valve that may be readily removed and replaced in order to permit the dispensing channel to be cleaned in case the need should arise.

I am aware that patents have been issued covering condiment dispensers having valves, stoppers or covers for the dispensing outlet and I have found that all of those which I have seen and tried have eventually failed to function properly when put into daily use.

The dispensers and valves or stoppers shown in this invention have been made and tried out and found to function very well and to overcome the greater part of the difficulties mentioned in the preceding discussion.

Other objects and advantages will become apparent and also details of construction will be brought out in the following specifications, reference being had to the accompanying drawing, wherein:

Fig. 1 is a side elevational view of a dispenser, parts being broken away and parts being shown in section to show the dispensing channel and valve or stopper.

Fig. 2 is a view similar to Fig. 1, but shows a slightly different type of stopper or valve.

Fig. 3 is a view similar to Fig. 1, but a modified type of dispensing channel is shown.

Fig. 4 is a side elevation of one type of stopper.

Fig. 5 is a side elevation of a slightly different stopper.

Fig. 6 is a sectional elevation of another design of stopper.

Fig. 7 is a view similar to Fig. 1, but shows a slightly different type of cap.

Fig. 8 is a view similar to Fig. 1, but shows a slightly different design of cap.

2

Fig. 9 is a side elevation of another modification of a valve or stopper.

Referring in detail to the drawing wherein like numerals are used to indicate like or similar parts in the various figures, Figs. 1, 2, 3, 7 and 8 represent typical applications of my invention to condiment dispensers having one dispensing opening or channel and in these figures 1 is the dispenser chamber or body and each of these bodies have 5 a neck or mouth 1a and these necks are provided with threads which engage corresponding intermeshing threads on the caps 2. 3 is the discharge nozzle or spout member and 3a is the dispensing channel or opening therein. These nozzle members and dispensing channels may be made of various shapes and materials to suit different methods of manufacturing and also to suit the valve or stopper.

In Fig. 1 the dispensing channel 3a is shown 10 enlarged at the outer end into a conical form and is made to suit the valve 4 which is cylindrical in shape with a spherical bottom. This is a preferred form as it has some advantages in that the valve seat forms a guide for the valve. 4a is the 15 stem for the valve 4. I find that a very satisfactory material for this stem is stainless steel spring wire of about twenty thousandth's of an inch in diameter, although a flexible plastic can also be used. This stem 4a is shown made up of 20 two substantially parallel wires. The upper ends have their ends bent and are cemented into the valve 4 and at the lower end of the stem the wires are bent substantially as shown into an elongated diamond shaped retainer 4b with the 25 width across the diamond made slightly greater than the diameter of the channel 3a, and this diamond shape acts as a retainer for the valve. Further, since the diamond retainer is flexible, the valve unit can be readily inserted in or removed from the dispensing channel in order to 30 clean same should the need arise. The stem 4a is made of sufficient length so that when the dispenser is inverted, the valve 4 will leave its seat on 3 and open the dispensing channel so that the contents of the dispenser may flow out 35 through the dispensing opening 3a. The valve stem must fit loosely in the channel so the valve 40 will open and close freely. In dispensers for material such as table salt, which readily absorbs moisture, it is advisable, if the salt contacts the 45 valve when flowing out of the dispenser, that the valve be made of a material that is of such porosity that any moisture which collects on same will be readily absorbed and penetrate into the 50 body of the valve or a material on which moisture 55 does not readily collect. I have found that valves

made of cork, porous wood, chalk, plaster of Paris and ceramic filter material work very well and the salt will not adhere readily to valves made of these materials. However, if the valve is made of a hard plastic material or rubber, the discharge opening will stop up in only moderately damp weather as a slight film of moisture will collect on the surface of the valve and the salt will adhere to same. Sudden changes of temperature will tend to cause a slight film of moisture to form on valves. This film of moisture will remain on the exterior of non-porous valves and salt will generally adhere to same. On porous materials the moisture will penetrate into the interior of the valve and the salt will have no, or only a very slight, tendency to adhere. This can be demonstrated by placing valves of porous and non-porous materials in a refrigerator and then bringing them out and immersing same in salt, or placing a small drop of water on the valves. The salt will not adhere to those valves made of a suitable porous material, but will generally adhere to those valves made of relative non-porous materials. Materials such as cork or porous paper or porous wood which are poor conductors of heat and have relative low heat absorbing capacity will have only a very slight condensation of moisture form on their exteriors when subjected to sudden temperature changes and I find that the salt has only a slight tendency to adhere to these materials.

For best results the valve should fit on the valve seat at the outer end of the dispensing channel so as to make a reasonably tight closure and, further, the valve seats so far as possible should be formed so that the salt will not lodge on or adhere to same and will be readily dislodged from the seats and passages during normal handling of the dispenser.

I find that in practically all dispensers that do not have a valve or stopper for the dispensing opening no matter how they are made or what materials are used, the salt within the dispenser will eventually become damp and ball up in damp weather and will not flow out through the dispensing outlet readily, if at all, when the dispenser is inverted. Gaskets 5 and 6 preferably of cork are used so that the discharge spout material does not contact the mouth or neck 1a of the container 1 or the cap 2. If gasket 6 is not used and 3 contacts the neck 1a a film of moisture will collect in the neck and the salt will build up on the inside of the neck. This is more pronounced when 3 is made of a hygroscopic material. I have not experienced any difficulty from salt collecting on and adhering to the stainless steel stem 4a in any appreciable quantity where it joins the valve when same is made of a hygroscopic material. This may be due to the small surface on same and the fact that the stem 4a will rub against the discharge channel during use. The stem may be covered with the valve material over a part of the upper portion as shown in Fig. 4, in which case the wires may be tied together just below this covering so that the covering material will not be broken off during insertion and removal of the valve unit.

In Fig. 2 the dispenser is very similar to Fig. 1 with the exception that the valve bottom and the seat are flat. The valve stem here is the sole guide for the valve and salt does not adhere readily to the valve seat. This type of valve and seat are easily made.

In Fig. 3 the dispensing nozzle 3 is formed integral with the cap 2 and the valve unit in Fig. 4 is shown. The stem 4a is enlarged or covered by

4c and the stem wires 4a are tied together by 4f when 4c is made of a fragile material. This enlarged portion 4c serves to partly obstruct the dispensing channel and it also permits the dispensing channel to be made larger and still get a desired rate of flow of condiment material through the dispensing channel. This dispenser is especially adapted for dispensing pepper and like condiments that are usually ground into finer particles than salt.

In Fig. 7 the discharge nozzle member 3 can be moulded in the cap and 3 may be made of such materials as plaster of Paris or cork.

In Fig. 8 the discharge nozzle member is a tube and this tube is cemented into cap 2. This tube can be made of suitable paper, plastic material or a material which readily absorbs moisture.

Figs. 4, 5, 6 and 9 are enlarged views of various modifications of valve units or stoppers.

Fig. 4 has already been described.

Fig. 5 shows the stopper unit used in Fig. 1 and has been described.

Fig. 6 shows a valve unit that is not readily removable as the stem 4d which may be made of plastic material is cemented or fastened into valve 4 after 4d is inserted in the channel 3a.

In Fig. 9 the underside of the valve 4 is shown with a ring of cork cemented to same and is the valve unit shown in Fig. 8. 4 may be of any suitable material that has sufficient weight to operate the valve.

In the valve units shown the valve may be made of wood, plastic, plastic with cork covering the lower portion of the valve, suitable moisture absorbing materials, or hygroscopic materials.

The dispensing nozzle member 3 may also be made of any of the above mentioned materials. I find that plaster of Paris is an excellent material to make both the valve member 4 and nozzle member 3 as this material is easily formed and has sufficient strength and wearing qualities to stand up under the wear which takes place in the nozzle channel 3a and that this material allows the moisture to penetrate readily enough so that table salt will not ordinarily adhere to the valve 4 or the nozzle member 3.

In my dispenser shown in my Fig. 7 I have used most frequently for the dispensing head 3 plaster of Paris which when wetted with water to form a plastic mixture sets or hardens into gypsum, after I had determined that gypsum thus formed was sufficiently hygroscopic to be used as a dispensing head for materials such as table salt. Plaster of Paris has the unusual property of expanding when setting into gypsum and when it is molded while in a plastic state in housing 2 this expansive force together with its adhesive and cementing qualities locks the head 3 securely in housing 2, and makes an excellent and an air and moisture tight fit where the head 3 contacts the interior surface of the encircling walls of the housing 2.

In making up the head 3 I generally place an excess of wetted plaster of Paris in housing 2. A ring gasket 6, preferably of cork, is next inserted in housing 2. I then place a disc of sheet plastic, a little smaller than the inside of housing 2 next to the underside of the gasket 6 and quickly screw the housing 2 on to the threaded neck or mouth 1a of the bottle or container 1, since plaster of Paris ordinarily hardens or sets very quickly. The excess plaster of Paris squirts out the hole in the top of housing 2 and this excess is removed. After the head 3 has set or hardened I unscrew housing 2 from neck 1a, remove the plastic disc and replace the housing on

the neck. I then drill a hole 3a in head 3 and thus form the dispensing channel.

Sometimes, when drilling the dispensing passage 3a in head 3, the head 3 becomes loosened in the housing 2 by the twisting action of the drill. This may be due to a variety of causes, it may be due to hard spots in the gypsum head 3 and also to the cap not being screwed down tightly enough on the container. Ordinarily the head is cemented in the housing very tightly and must be driven out to remove same. However, when the head 3 loosens up in housing 2 as the dispensing passage 3a is being drilled, I re-cement the head 3 in housing 2 by coating the head preferably with wetted plaster of Paris, or I sometimes use a suitable plastic cement, and then insert the head in housing 2. I then screw the housing 2 on to the neck or mouth 1a. In applying the cementing coating to the head I use an excess so that the plastic cementing material will be forced out of the housing 2 at the top opening and also at the gasket 6. Any air in the housing is thus forced out and voids and air spaces are thus prevented from forming between head 3 and housing 2, and I thus secure substantially the same effect as where I cast or mold the whole head 3 in housing 2.

My method of casting and molding the head 3 in housing 2 and also of cementing an already formed head 3 in housing 2 where I use an excess of plastic cement has several important advantages.

I avoid, by completely filling the housing 2 above gasket 6, and by driving out any air therein by using an excess of plastic material, the formation of air spaces or voids between head 3 and the inside walls of housing 2. Further, by using a material for the head 3 which expands when setting and which also has adhesive and cementing qualities, I lock and cement the head 3 very securely in and to the inside walls of housing 2, which are generally smooth and difficult to cement to, so that air or moisture cannot enter therebetween. And by cementing gasket 6 to the underside of head 3 I avoid air spaces or voids here and prevent air or moisture from collecting therebetween and dampening the gasket 6.

If voids or air spaces exist between the head 3 and the inside of the housing 2 and head 3 is not cemented to the inside walls of housing 2 as I describe same, damp air will be drawn into these spaces or voids during a damp cool period since the air in these voids will contract when cooled and produce a slight vacuum. And, further, the moisture in this drawn in damp air will condense on the housing at these voids since the housings 2 are made of metal, glass or plastic which readily condense moisture from damp air when cooled. This moisture accumulates during successive periods of damp air and eventually dampens head 3 and a damp head 3 will dampen the air and hence the salt within container 1. Salt will also adhere to and be absorbed by a head 3 that is damp.

If head 3 is not cemented to the inside walls of housing 2 with an air and moisture tight joint any salt that may lodge on the top of the cap where the head 3 joins housing 2 will dissolve in damp weather and seep down between head 3 and housing 2 where head 3 will absorb this dissolved salt.

When head 3 absorbs dissolved salt I find that it will not dry out but has a strong tendency to remain damp and salt will adhere to same and when this dampness reaches a certain point the

dispensing passage will become clogged with salt and the dispenser will not function.

When head 3 is not cemented to housing 2 it will loosen up every time the cap is removed from the container and it frequently becomes crossed positioned. This results in increased voids between head 3 and housing 2 and I find that the greater these voids are the quicker the head becomes damp in damp weather.

10 My salt dispensers have proven by comparative tests to be, even when not using my stoppers, from 3 to 5 times more effective in keeping the salt within the container dry and free flowing than other salt cellars now on the market and using a solid one piece dispensing head made of a hygroscopic material and with a dispensing channel formed or molded therein and without caps or stoppers. This is due to the fact that there are in these other salt dispensers voids or air spaces between the heads and the housings and also because these other heads are not cemented in the housings with an air and moisture tight joint, because I find when I cement these other hygroscopic dispensing heads of these other salt dispensers into their housings their performance is improved from 3 to 5 times.

15 I find from comparative tests that it is much more important, where one uses a hygroscopic dispensing head, to cement the head in the housing than it is to secure an air tight fit of gasket 6 on neck 1a.

20 I find that in my salt dispensers the head does during normal use absorb some salt. How long it will require before my heads 3 become sufficiently damp so that the dispensing passage becomes clogged I do not know as I have not been able to test them long enough to find out, but it is several times longer than salt shakers with hygroscopic dispensing heads now on the market, and which do not have caps or stoppers, as proven by comparative tests.

25 When my dispensing heads 3 do become dampened by dissolved salt, this salt may be removed by soaking the whole cap in fresh water for several hours and then drying same in a moderately warm place for a day or so. The above dampening occurred when my salt cellars were kept for testing purposes for several days, and sometimes as long as three weeks, in a covered pan with water in same to produce a damp atmosphere and where the salt shakers were tested daily.

30 If a light material such as porous wood or cork is used for the valve 4 a weight would have to be imbedded in same to insure that the valve would open when the dispenser is inverted.

35 The dispensers and valve units may readily be made in many other ways than shown in the drawings and I do not wish to be limited to the precise details of construction set forth, but desire to avail myself of such variations and modifications as come within the scope of the appended claims.

40 What I claim is:

45 1. In combination, a dispenser comprising a container having a mouth, a dispensing cap forming a closure for said mouth, said cap being provided with a channel affording communication between the interior and exterior of said container, a valve comprising a hygroscopic material shaped to rest on and close said channel when said dispenser is in an upright position, a guiding and retaining stem attached to said valve at one end and fitting loosely in and extending through said channel and having retaining means at the other end, said stem being of such length that

when the said dispenser is inverted the said valve will leave its seat on and open said channel.

2. In combination, a dispenser comprising a container having a mouth, a dispensing cap forming a closure for said mouth, said cap being provided with a channel affording communication between the interior and exterior of said container, a valve comprising a hygroscopic material shaped to seat on and close said channel when said dispenser is in an upright position a guiding and retaining stem attached at its upper end to said valve and fitting loosely in and extending through said channel and having retaining means at its lower end, said stem being made of such length that when the said dispenser is in an inverted position the said valve will leave its seat on and open said channel, said stem being made up of flexible spring material with its lower end formed into a flexible retaining head having the horizontal width of said retaining head slightly wider than the inside horizontal dimension of said channel.

3. A detachable valve and retaining unit for the dispensing channel leading from the interior of a condiment container, said unit comprising a valve of hygroscopic material shaped to close said channel at its outer end, a retaining and guiding stem attached at one end to said valve and a flexible retaining head at the other end, said stem designed to fit loosely in said channel, the length of said stem between the valve and retaining head being longer than said channel and the width of said flexible retaining head being slightly wider than the width of said channel.

4. In combination, a dispenser comprising a container having a mouth; a dispensing head forming a closure for said mouth, said dispensing head having a channel affording communication between the interior and exterior of said container; a valve comprising a hygroscopic material shaped to rest on and close said channel when said dispenser is in an upright position, a guiding and retaining stem attached to said valve at one end and extending through said channel and having retaining means at the other end, said stem below said valve being covered by a hygroscopic material and said stem covering being of such outside diameter as to fit loosely in said channel, and said stem being of such length that when said dispenser is inverted the said valve will leave its seat on and open said channel.

5. In combination, a dispenser for finely divided material susceptible to caking when and after being exposed to moist air; comprising: a container having a mouth; a dispensing head forming a closure for said mouth, said dispensing head comprising a hygroscopic material and provided with a dispensing channel affording communication between the interior and exterior of said container, said head being formed and moulded in said mouth while said material is in a plastic condition and said material having the property of setting and forming a unitary hygroscopic body and also of expanding while setting, whereby said head is sealed in said mouth where said head adjoins said mouth.

6. In combination, a dispenser for finely divided material susceptible to caking when and after being exposed to moist air, comprising: a container having a mouth; a dispensing cap forming a closure for said mouth, said cap comprising, a dispensing head and a housing member for attaching said head to said container,

said head being formed and moulded in said housing while the material forming said head is in a plastic condition and said material having the property of setting and forming a unitary hygroscopic body and also of expanding when setting, whereby said head is sealed in said housing, where said head adjoins said housing, and said head being provided with a dispensing channel affording communication between the interior and exterior of said container.

5 7. In combination, a dispenser for finely divided material susceptible to caking when and after being exposed to damp air, comprising: a container having a mouth; a dispensing cap forming a closure for said mouth, said cap comprising, a dispensing head and a housing member for attaching said head to said container; the material comprising said head being placed in and molded in said housing to form said head while the said material is in a plastic condition and said material having the property of setting and forming a unitary body of hygroscopic material and of adhering to a contacting surface, whereby said head is cemented to the interior 20 surface of the walls of said housing which encircle and contact said head, and said head being provided with a dispensing channel which affords communication between the interior and exterior of said container.

30 8. In combination, a dispenser for finely divided material susceptible to caking when and after being exposed to damp air, comprising: a container having a mouth; a dispensing head forming a closure for said mouth, said head comprising a hygroscopic body having therein a dispensing passage affording communication between the interior and exterior of said container, said head being placed and molded in said mouth while material comprising same is in a plastic condition and said material having the property of expanding while setting from a plastic to a solid condition.

35 9. In combination, a dispenser for finely divided material susceptible to caking when and after being exposed to damp air, comprising: a container having a mouth; a dispensing cap forming a closure for said mouth, said cap comprising, a dispensing head and a housing member encircling and contacting said head for attaching said head to said container at said mouth, said head comprising a hygroscopic body with a dispensing passage therein which affords communication between the interior and exterior of said container, and said head being placed and molded in said housing while material comprising same is in a plastic condition, and said material having the property of expanding while setting from a plastic to a solid state.
